J. Perry Hinman, Esq., Attorney BY

UNITED STATES PATENT OFFICE

JOHN GOOD, OF GARDEN CITY, NEW YORK, ASSIGNOR TO GOOD INVENTIONS CO., OF NEW YORK, N. Y., A CORPORATION OF NEW YORK

FUEL SPRAYING

Application filed January 9, 1925. Serial No. 1,452.

The object of the invention is an efficient spraying means for oil burners and other purposes, not dependent on the use of fine spray orifices subject to stoppage by dirt in the oil or liquid, and also a spray regulation means capable of varying the volume of the spray without affecting its quality or velocity to an extent sufficient to affect or materially change the character of the combustion or the susceptibility of the spray for ignition by spark, if that form of ignition is employed; and also a new method of spraying fuel as below explained.

In the accompanying drawing, Figs. 1 and 15 2 are respectively axial section and rear elevation of a burner head incorporating one form of the invention, and Figs. 3 and 4 are respectively rear elevation and axial section of a modified form.

20 Referring first to Figs. 1 and 2, the device comprises a body or casing 1, which is flanged or otherwise formed for attachment to the combustion chamber or spray space, not shown. This casing carries the nozzle 2 containing a liquid supply passage 3 and a spraying orifice 4. The orifice constitutes the source of the spray and may be variously organized for this purpose; in the present case it is occupied by a spiral-vaned plug cen-

25 trally supported therein by the screw stem 5 and adapted to shatter the liquid and give it a whirling motion as it issues from the orifice, under the pressure of the liquid supplied, this being a usual method of spraying oil by a pump or other source of pressure. Other types of spray sources can be substituted with equal effect whether operating solely by the pressure of the supplied liquid, as in the present case, or by air-jet or steam blast.

30 According to this invention, the emergent spray is intercepted by a member 6 carried on a sleeve or support 7 fitted to be moved back and forth in the direction of the axis of the spray as by means of a rack and pinion such as shown at 8, or in any other appropriate way. The liquid in the spray which strikes the interceptor member 6 is deflected or diverted thereby into the lower part of the sleeve 7 or nozzle structure whence it passes into return passage 9. This return

passage may conduct the diverted liquid back to the reservoir constituting the source of liquid supply, or to any other place of storage or use not shown. The liquid which escapes the interceptor passes to the combustion space. 55 Inasmuch as the spray is divergent or coniform, as indicated by the dotted lines, it will be apparent that the axial distance by which the interceptor is separated from the spraying orifice will control the amount of sprayed 60 liquid which is diverted into the return passage and thereby control the amount which reaches the combustion space. When the sleeve is set in its innermost position, about as indicated by the full lines in Fig. 1, practically the whole of the spray passes to the combustion space; when it is set to the left-hand position, indicated by dotted lines, only 65 a part of the spray reaches the combustion space, the balance being diverted into the return passage. In both adjustments, however, it will be seen that the velocity and degree of fineness of atomization of the spray which reaches the combustion space are unchanged, and if these factors have been properly established in the first instance, they will continue 70 the same at all rates of combustion, thus making it possible to vary the rate without affecting the burner efficiency.

75 Preferably the interceptor has the form of an annular plate, concentric to the spray orifice, as indicated, so that the central part of the spray escapes it. It has been found desirable to supplement this plate with a second guard plate 10, having a somewhat 80 larger central opening, the purpose of which is to intercept and return such liquid as happens to be turned outwardly by reason of its contact with the edge of the main interceptor and to act as a heat screen. When 85 this doubled interceptor is used, the main plate 6 is provided with an opening 11 through which liquid in front of it may pass to the return passage 9. The pinion 8 is arranged to be operated by a thumb wheel 90 outside of the burner head and is supplied with a friction washer 16 to hold the adjustment. The screw and slot at the top of the casing are to limit the adjustment and prevent rotation of the sleeve. 95 100

In the form of Figs. 3 and 4, the burner head comprises a one-piece casting 12, having a supply passage 3 and a spray orifice 4 as in the form first described, but in this case the interceptor is formed as a scoop 13 hinged in a chamber 14 below the nozzle proper, which chamber delivers or drains into the return passage 9. The upper edge of the scoop 13 intercepts more or less of the emergent spray according to its position which can be set as desired by means of the thumb wheel 15 on the end of its hinge shaft. A friction washer 16 is applied also to this thumb wheel to prevent movement of the interceptor by the force of the spray or by vibration. The method of operation is the same in both forms, however, and consists in causing the fuel to be atomized as a spray and then selecting from such spray the portion best suited to be burned and collecting the remaining portion and returning it through the spray nozzle.

From the description of the foregoing forms of the invention, it will be apparent that the effects described can be secured in various other mechanical embodiments and it will therefore be understood that no limitation is herein intended to the particular structures shown.

30 I claim:

1. Liquid spraying apparatus comprising a unitary head structure having a spray source orifice and a liquid chamber therein, a supply passage leading to the spray orifice 35 and a return passage leading from said chamber, an adjustable member extending into the spray cone to intercept a portion only of the spray and adapted to direct variable amounts of the sprayed liquid into said chamber.

40 2. Liquid spraying apparatus including a liquid supply passage terminating in a spray source and means for varying the volume of liquid discharged comprising a transverse interceptor member apertured concentrically with the spray axis and movable along the same toward and from the spray source.

3. Liquid spraying apparatus as claimed 50 in claim 2 in which the interceptor comprises a pair of annular members spaced longitudinally of the spray cone axis.

4. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage 55 from said chamber by which said collected fuel spray is drained.

60 5. A burner comprising a body having a chamber therein, an atomizing nozzle adapt-

ed to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage from said chamber by which said collected fuel spray is drained, a fuel supply reservoir into which said passage discharges.

70 6. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage from said chamber by which said collected fuel spray is drained, a fuel supply reservoir into which said passage discharges and a pump interposed between said reservoir and said nozzle adapted to establish pressure to project said spray.

75 7. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage from said chamber by which said collected fuel spray is drained, a heat screen beyond and spaced from said plate and having an aperture in said axial alignment to admit the projection of said center portion of said spray and a discharge duct from the space 80 between the plate and the heat screen to return condensed spray therein to a reservoir, a fuel reservoir into which said passage and said duct are adapted to drain and means constructed and adapted to abstract fuel from said reservoir and project the same through said nozzle.

8. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage from said chamber by which said collected fuel spray is drained and means for varying the distance between the plate and the nozzle to vary the volume of said center portion of said spray passing through said aperture.

9. A burner comprising a body having a chamber therein, an atomizing nozzle adapted to project fuel with a rotary motion and as a conical shaped spray into said

- chamber, a plate having an aperture substantially axially aligned with said nozzle whereby the center portion of said spray is passed through said aperture and the remainder of said fuel spray is collected in said chamber, a passage from said chamber by which said collected fuel spray is drained, a fuel supply reservoir into which said passage discharges, and means for varying the distance between the plate and the nozzle to vary the volume of said center portion of said spray passing through said aperture. 5
10. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of said fuel spray is collected in said chamber, a passage from said chamber by which said collected fuel spray is drained, a fuel supply reservoir into which said passage discharges and a pump interposed between said reservoir and said nozzle adapted to establish pressure to project the said spray, and means for varying the distance between the plate and the nozzle to vary the 20 volume of said center portion of said spray passing through said aperture. 25
11. A burner comprising a body having a chamber therein, an atomizing nozzle adapted to project fuel with a rotary motion and as a conical shaped spray into said chamber, a plate having an aperture substantially axially aligned with said nozzle whereby the center portion of said spray is passed through said aperture and the remainder of 30 said fuel spray is collected in said chamber, a passage from said chamber by which said collected fuel spray is drained, a heat screen beyond and spaced from said plate and having an aperture in said axial alignment to admit the projection of said center portion of said spray and a discharge duct from the space between the plate and the heat screen to return condensed spray therein to a reservoir, a fuel reservoir into which said passage and said duct are adapted to drain and means constructed and adapted to abstract fuel from said reservoir and project the same through said nozzle, and means for varying the distance between the plate and the nozzle to vary the volume of said center portion 35 of said spray passing through said aperture. 40
12. The method of producing a selected fuel spray from a burner which consists of causing the fuel to be atomized as a conical spray and then selecting from said conical spray the portion to be burned and collecting the other portion of said spray and again passing said collected portion through said nozzle with additional fuel. 45
13. The method of producing a selected fuel spray from a burner which consists of causing the fuel to be atomized as a conical spray and then selecting from said conical spray the portion to be burned and collecting the other portion of said spray and again passing said collected portion through said nozzle and varying the relative quantity of said central portion to suit the load requirements of said burner. 50
14. The method of producing a selected fuel spray from a burner which consists of causing the fuel to be atomized as a conical spray and then selecting from said conical spray the portion to be burned and collecting the other portion of said spray and again passing said collected portion through said nozzle with additional fuel and varying the relative quantity of said portions to suit the requirements of said burner. 55
- In testimony whereof, I have signed this specification.
